C. H. LEONARD,
DRIP CUP FOR REFRIGERATOR TRAPS,
APPLICATION FILED OCT. 9, 1916.

1,228,034.

Patented May 29, 1917.

UNITED STATES PATENT OFFICE.

CHARLES H. LEONARD, OF GRAND RAPIDS, MICHIGAN, ASSIGNOR TO GRAND RAPIDS
REFRIGERATOR CO., OF GRAND RAPIDS, MICHIGAN, A CORPORATION OF MICHIGAN.

DRIP-CUP FOR REFRIGERATOR-TRAPS.

1,228,034.

Specification of Letters Patent. Patented May 29, 1917.

Application filed October 9, 1916. Serial No. 124,625.

To all whom it may concern:

Be it known that I, CHARLES H. LEONARD, a citizen of the United States of America, residing at Grand Rapids, in the county of Kent and State of Michigan, have invented certain new and useful Improvements in Drip-Cups for Refrigerator-Traps; and I do hereby declare the following to be a full, clear, and exact description of the invention, such as will enable others skilled in the art to which it appertains to make and use the same.

This invention relates to refrigerator constructions and especially to a novel construction of drip cup for traps for refrigerators. In a refrigerator the water coming from the ice box is passed through a drain pipe or conduit to the outside of the refrigerator and ordinarily a trap is interposed in the length of the conduit for sealing against the entrance of air into the ice box therethrough. The water from the ice being substantially at a temperature of 32 degrees Fahrenheit cools the surrounding air 20 below the provision box, whereby during humid weather the lower part of the conduit collects moisture on the outside or as is commonly known "sweats." This is a disadvantage in a refrigerator construction as 25 the collected moisture running down the outside of the conduit comes in contact with the bottom of the refrigerator which being of wood swells and in the course of time decays or is otherwise damaged rendering 30 the life of the refrigerator less than it would otherwise be. It is the object and purpose of the present invention to provide a refrigerator trap with a drip cup in which the cold water may be carried to the outside 35 side of the refrigerator without coming into contact with the lower part of the conduit leading to the outside whereby this part of the conduit is not lowered in temperature and the collection of moisture on the outside does not take place. To attain this end 40 I have embodied my invention in a construction disclosed in the accompanying drawing in which;

Figure 1 is a partial perspective and sectional view illustrating the drain trap and drip cup as applied to a refrigerator construction.

Fig. 2 is an elevation of the drip cup in its preferred form, and

Fig. 3 is a plan view thereof.

Like reference characters refer to like parts throughout the several views of the drawings.

The refrigerator to which my invention is applied is of the usual character and contains in its construction horizontal partitions 1 and 2, and a bottom 3 secured together at their rear ends by a back 4. The provision compartment is located between partitions 1 and 2 said compartment having a lining 5 of any desired type, preferably of sheet metal coated on its inner side with porcelain. The ice compartment is above the partition 1 and the water that is given off as the ice melts drains from the ice compartment through a funnel 6 or the like into a pipe 7 which adjacent its lower end has an enlarged dome shaped member 8 secured thereto formed with an outwardly projecting bead 9 around it which is adapted to rest against the upper edges of a cylindrical member 10 of sheet metal open at its upper end and into which the lower portion of the member 8 inserts. As the air in the provision compartment is usually dry and of practically the same temperature as the water dropping in pipe 7, no moisture collection occurs on such pipe. Member 10 has a laterally projecting flange at its upper end which rests against the lining 5 around an opening cut therein through which member 10 is passed as shown. There is provided in the sides of the member 10 a plurality of screw threads for the reception of an outer member 12 which screws thereon and has a laterally extending flange 13 at its upper end adapted to lie beneath the lining 5, it being apparent that by means of this structure members 10 and 11 may be locked in place on the lining 5. The lower end of the member 10 is reduced in diameter as indicated at 14 and extended through the bottom 3 of the refrigerator.

Within member 10 a drip cup 15 is located which has downwardly and inwardly inclined sides as indicated at 16 forming in effect a conical cup from the lower end of which depends a wire or rod 17. This wire or rod extends through the extension 14 being located centrally thereof the wire 17 and cup 15 being free from contact with the sides of said member 10. The drip cup is held in place by means of the plurality of upwardly and outwardly extended and curved ears 18 extending from the upper

edges of the cup which are adapted to engage with the upper depression in member 10 formed by the screw threads therein. In practice these ears are strengthened by 5 corrugations 19.

10 The lower end of the pipe 7 below the dome 8 extends into the drip cup for a distance. Water entering through pipe 7 fills the cup and, as will be apparent, when the 15 cup is full the lower end of pipe 7 is sealed against the entrance of any air through the pipe into the ice compartment. The overflow of the cup passes down the outside thereof being dammed back by the upwardly turned ears 19 from reaching the outer member 10, and to the wire 17 and thence along the wire to the end from which it may drop to any suitable drain or receptacle.

20 With a construction of the character described, it will be evident that the ice cold water does not come in contact with the member 10 or the extension 14 thereof. The air between the partition 2 and bottom 3 accordingly keeps member 10 at substantially an even temperature therewith and no collection of moisture on the outside of the member 10 from this air can take place. Heretofore the water from the ice box has 25 contacted with said member 10 and any collection of moisture on the outside thereof has been passed to the base 3 which being of wood swells and warps and is much more quickly destroyed than would otherwise be 30 with the base kept in dry condition. The construction outlined attains this end by means of very simply and easily manufactured device which may be quickly and easily applied to refrigerator drain pipes 35 and traps.

40 Various changes in minor detail of structure may be resorted to without departing from the invention. While the drip cup described with the upwardly and outwardly turned ears for damming back and preventing any of the water getting to the member 45 10 is a practical and preferred type of construction, it is apparent that various other modified devices may be used to attain the same end so long as the water entering the 50 drip cup is compelled to pass down the outside thereof and not come into contact with the inner sides of the member 10. Accordingly I do not wish to be limited to the 55 exact specific structure disclosed but consider myself entitled to all modifications of structure which fall in the scope of the appended claims defining the invention.

I claim:

60 1. In a device of the character described, a cylindrical sheet metal member provided with a plurality of screw threads in the sides thereof, a cup having an open upper end and downwardly and inwardly inclined sides coming substantially to a point, a rod

depending from said point of the cup through said member, said cup and rod being free from contact with the inner sides of the member, and a plurality of outwardly extending ears on the cup engaging at their ends with the grooves formed in the member by said screw threads. 70

2. In a device of the character described, a cylindrical member adapted to be connected with a refrigerator, a cup having an open upper end and downwardly and inwardly inclined sides substantially to a point, a rod depending from the cup from 75 said point, and means for securing the cup within said member and positioning it therein so as to hold the sides of the cup and said rod from contact with the inner sides of the member. 80

3. In a device of the character described, a sheet metal member having open ends and adapted to be connected with a refrigerator, a cup having an open upper end and downwardly and inwardly inclined sides coming substantially to a point, a rod depending from said cup at said point, means for 85 securing the cup and rod within said member with the sides of the cup and the rod free from contact with the inner sides of the member, a tube having its lower end entered a distance into the cup, and a dome in 90 the tube inserting into the upper end of said member and engaging therewith to limit the distance that the end of said tube enters into the cup. 95

4. In a device of the character described, a substantially cylindrical member having open ends, a cup having an open end and sides turned downwardly and inwardly, a rod depending from the bottom of the cup, and a plurality of ears at the upper edges 100 of the cup, turned outwardly and upwardly therefrom and engaging with the inner sides of said member to position the cup and rod depending therefrom with the sides of the cup and rod free from contact with the 105 inner sides of the member. 110

5. In combination, a cylindrical member having open ends adapted to be attached to a refrigerator, a tube leading into said member at its upper end, a dome secured to the tube inserting into the upper end of said member, a bead in the dome for determining the extent of the entrance of the tube into the member, a cup having an open upper end within the member into which the end of the tube extends, downwardly and inwardly turned sides to the cup a rod depending from the lower end of the cup through the member, and ears on the cup projecting laterally and upwardly and engaging against the inner sides of said member to position the cup and rod free from contact with the member. 115 120

6. In a device of the character described, a hollow member having open ends adapted 130

to be connected with a refrigerator, a cup having an open upper end and sides turned downwardly and inwardly located within the hollow member, said cup being adapted 5 to receive water given off by the ice in the refrigerator and means including an elongated extension depending from the lower

end of the cup for causing the water which flows from the drip cup to run down the outer sides of the cup and not come in contact with the inner sides of said hollow member.

In testimony whereof I affix my signature.
CHARLES H. LEONARD.
